H. J. ROGGENKAMP.
WIRE CLAMP.
APPLICATION FILED AUG. 16, 1916.

Patented May 14, 1918.

FIG. 1

FIG. 2

FIG. 3

UNITED STATES PATENT OFFICE.

HANS J. ROGGENKAMP, OF FIRESTEEL, SOUTH DAKOTA.

WIRE-CLAMP.

1,265,817.

Specification of Letters Patent. Patented May 14, 1918.

Application filed August 16, 1916. Serial No. 115,304.

To all whom it may concern:

Be it known that I, HANS J. ROGGENKAMP, a citizen of the United States, residing at Firesteel, in the county of Dewey, State of 5 South Dakota, have invented certain new and useful Improvements in Wire-Clamps; and I do hereby declare the following to be a full, clear, and exact description of the invention, such as will enable others skilled 10 in the art to which it appertains to make and use the same.

The present invention is directed to improvements in clamps for use in connection with wire stretchers.

15 The invention has for its object to provide a device of this character constructed in such a manner that the wire when engaged between the jaws of the device will be firmly clamped when strain is applied to the 20 vice.

A further object of the invention is to provide a device of this character constructed in such a manner that the wire when engaged between the jaws will be firmly 25 clamped and held against lateral movement relative to the jaws.

With these and other objects in view, this invention resides in the novel features of construction, formation, and arrangement 30 of parts to be hereinafter more fully described, claimed, and illustrated in the accompanying drawing in which:—

Figure 1 is a perspective view of the device in its inoperative position.

35 Fig. 2 is a similar view showing the device in use.

Fig 3 is an end view.

The device consists of a pair of handles 1 and 2, disposed in crosswise relation and 40 pivotally connected by the pin 3. The handles are bent outwardly and have their inner ends provided with eyes 4 having engaged therewith one of the ends of the chain sections 5, the adjacent ends of which are 45 connected by a ring 6 to which is connected a hook 7. The hook 7 can be attached to any conventional form of wire stretcher, or to any other suitable tool, as desired.

The forward end of the handle 2 terminates in oppositely directed lateral jaws 8, 50 the outer ends of which are provided with right angle lips 9. The handle 2 terminates at its outer end in oppositely directed lateral jaws 10 which are adapted to coact with the jaws 8 to clamp the wire upon 55 either side of the handles 1 and 2. The confronting faces of the jaws 8 and 10 are serrated as at 11 so as to firmly grip the wire when the jaws are in their clamped position.

It is obvious that when strain is applied 60 so as to draw the handles 1 and 2 toward each other the jaws will firmly clamp the wire. By providing the lips 9 the wire will be prevented from moving laterally in one direction, while the handles of course will 65 prevent the wire from lateral movement in an opposite direction.

The coil spring 12 is provided, and has its ends connected to the rear ends of the handles 1 and 2, said spring serving to hold 70 the jaws in yielding engagement so that the wire can be initially clamped therebetween.

It will be further noted that by providing the lateral jaws 8 and 10 that the wire can be gripped upon either side of the handles 75 1 and 2.

What is claimed is:—

A device of the class described, comprising a pair of pivotally connected handles adjacent ends of each of which terminates in 80 a pair of transversely disposed jaws of relatively narrow width and having their planes disposed at right angles to those of said handles, the inner adjacent faces of said jaws being serrated and one pair of said 85 jaws having angular lips formed upon the outer ends thereof and of the same width as said jaws and adapted to overlap the end of the adjacent jaw of the other pair when said jaws are in their operative positions. 90

In testimony whereof, I affix my signature, in the presence of two witnesses.

HANS J. ROGGENKAMP.

Witnesses:

AUGUSTIN BRISTOL,
FRED G. CURRY.
